DESIGN FOR A DOLL BABY

A Lester Gaba, New York, N. Y., assignor to Kerk Guild, Inc., Utica, N. Y., a corporation of New York

Application November 21, 1934, Serial No. 54,107

Term of patent 3½ years

To all whom it may concern:

Be it known that I, A Lester Gaba, a citizen of the United States, residing at 237 E. 20th St., New York, in the county of New York and State of New York, have invented a new, original, and ornamental Design for a Doll Baby, of which the following is a specification, reference being had to the accompanying drawing, forming part thereof.

In the drawing:

Fig. 1 is a perspective view of a doll baby showing my new design.

Fig. 2 is a rear elevation.

Fig. 3 is a vertical sectional view taken on line 3—3 of Fig. 2, and

Fig. 4 is a horizontal sectional view taken on line 4—4 of Fig. 2.

I claim:

The ornamental design for a doll baby as shown.

A LESTER GABA.
